Attns,

UNITED STATES PATENT OFFICE.

JOHN H. JUNKINS, OF UPPER SANDUSKY, OHIO.

IMPROVEMENT IN CORN-DROPPERS.

Specification forming part of Letters Patent No. 129,963, dated July 30, 1872; antedated July 27, 1872.

To all whom it may concern:

Be it known that I, JOHN H. JUNKINS, of Upper Sandusky, in the county of Wyandot and State of Ohio, have invented a new and valuable Improvement in Corn-Droppers; and I do hereby declare that the following is a full, clear, and exact description of the construction and operation of the same, reference being had to the annexed drawing making a part of this specification, and to the letters and figures of reference marked thereon.

Figure 1 of the drawing is a representation of a plan view of my invention. Fig. 2 is a vertical longitudinal section, and Fig. 3 is a side elevation of the same.

This invention has relation to corn-droppers; and the novelty consists in the general construction and arrangement of the parts of an implement designed to be carried and operated by a person walking, and adapted to drop the grains of corn in proper quantities and at regular intervals, as hereinafter described.

In the drawing, A represents a rectangular box, inclosing a hopper, B, having an opening at its lower end for the seed-cylinder to pass through. The cylinder C is journaled transversely to the box A below the hopper, its circumference passing through the opening in the hopper. The end of the shaft of the cylinder passes through one side of the box, and is armed with an operating-crank, D. E indicates a box, within which the cylinder revolves, and which serves to prevent the loss of the grain before it passes to the tapering spout F, which is secured to the lower part of the box E. G represents a cup, formed in the

cylinder C, for the purpose of receiving the corn to be planted. The upper part of said cup is cut away, as shown, so that the cup will be filled more easily. The cylinder performs a half revolution, receiving the corn, planting it, and returning for another supply. The revolution of the cylinder is checked by two blocks, d d, projecting from one side of the box A, and acting as stops to the arm D. The implement is supported by a cord, e, which is thrown over the shoulder of the operator, and is attached to rings d' at either end of the box A. The ends of one side of the box A are extended out at the top to form arms H H', the former of which serves as a handle to be taken hold of with the right hand. A curved board, I, rests on the arm H' and the adjacent end of the box, and is shaped to the form of the body, against which it rests. K indicates a brush, consisting of bristles secured by a cleat, L, their ends touching the cylinder. This brush is intended to prevent the loss of grain by waste.

What I claim as my invention, and desire to secure by Letters Patent, is—

The improved hand corn-planter having the box A, hopper B, waist-board I, seed-cylinder C, brush K, crank D, blocks or stops d d, spout F, and cord e, all constructed and arranged substantially as specified.

In testimony that I claim the above I have hereunto subscribed my name in the presence of two witnesses.

JOHN H. JUNKINS.
